UNITED STATES PATENT OFFICE

CHARLES STANLEY RHOADS, JR., OF INDIANAPOLIS, INDIANA.

ANSWER-BACK FOR SIGNALING SYSTEMS.

1,309,369.

Specification of Letters Patent.

Patented July 8, 1919.

Application filed February 25, 1918. Serial No. 218,943.

To all whom it may concern:

Be it known that I, CHARLES STANLEY RHOADS, Jr., a citizen of the United States, residing at Indianapolis, in the county of Marion and State of Indiana, have invented a certain new and useful Improvement in Answer-Backs for Signaling Systems, of which the following is a full, clear, concise, and exact description, reference being had 10 to the accompanying drawings, forming a part of this specification.

My invention relates to answer back apparatus for signaling systems and has for its object the provision of an improved 15 answer back system which is of particular use in connection with telegraph or similar systems.

In the specification and drawing I have shown a system of this nature as applied 20 more particularly to a telegraph system, as the application of the invention to other systems will be readily apparent from this description.

I will describe this form of my invention 25 by referring more particularly to the accompanying drawing illustrating this particular embodiment.

In this drawing I show a Morse telegraph line 1 which as customary extends directly 30 through a plurality of stations. For the sake of clearness I have merely shown a sending station A and a receiving station B. In practice, of course, there will be a great number of such receiving stations, but 35 as stated, there is no need of illustrating more than one for the purposes herein.

At the sending station I have shown a telegraph line 1 having the key 2 with customary short circuiting switch 3, the telegraph line 1 being at this sending station 40 connected to earth at 4 through the interposition of the telegraph battery 5. A relay 6 is also shown at this sending station operating the customary sounder 7 which is associated in the local circuit with the battery 8. The substations are each provided with a selector 9 which may be of the customary Gill telegraph selector type as shown for instance in his Patent No. 906,523 and having 45 the operating winding 10 together with the contacts 11 and 12 which are brought into circuit closure when a definite dot and dash code signal has been passed through the circuit including the coil 10. The construction of this selector is well known in

the telephone art and it is thought a further description of this code selector will not be needed for the purposes herein. The opposite extremity of the line 1 again is grounded at 13 through a battery 14. 60 This selector 9 at the station B is adapted to operate the call bell 15 whenever the proper code is received over the line 1 by the selector 9.

The circuit shown for station B is amplified so that it is fully equipped for use in connection with concentration units used upon tables at those telephone exchanges where many lines enter. The line 1 is thus shown at the substation B and is provided 70 with two jacks 16 and 17 respectively, to either of which jacks connection may be made by the plug 18 being directly connected to a relay 19 and telegraph key 20. The jacks 16 and 17 are at opposite sides of the 75 table so that connection may be made from either side. In connection with the jacks 16 and 17 respectively I provide lamps 21 and 22, which are illuminated whenever a call has been received over that particular 80 line, which call remains unanswered. There is further provided a pilot relay 23 to control a pilot lamp 24, which pilot lamp and relay may be common to a plurality of entering lines to signal an operator so that 85 he may answer the call that has come in. The jacks are provided with sleeve contact springs 25 and 26 respectively and with tip contact springs 27 and 28 respectively. The springs 27 and 28 are insulated from, but 90 cause the simultaneous movement therewith of coöperating contact springs 29 and 30. Back contacts 31 and 32 are respectively provided for the springs 27 and 28 and back contacts 33 and 34 respectively are provided 95 for the springs 29 and 30. Call bell 15 is controlled intermediate the selector 9 by a double wound relay 35 having the coils 36 and 37 respectively, which are wound to one hundred ohms resistance and thirty thousand ohms resistance. The relay 35 has an armature 38 which is connected to ground at 39, this armature having the front contact 40. The call bell has an operating magnet 41 controlling an armature 42 having 100 a back contact 43. The armature 42 also causes the simultaneous movement therewith of a contact spring 44, which however is insulated from the armature 42, and this contact spring 44 coöperates with a back 110

contact 45. The pilot relay 23 has an armature 46 which is directly connected to ground at 47 through the interposition of the preferably fifty-two volt battery 48. One terminal of the pilot lamp 24 is connected to ground at 49. A locking relay 50 is provided having the armature 51 coöperating with the front contact 52, one terminal of the coil 50 being directly connected to ground at 53. The locking relay 50 preferably has about four ohms resistance and the pilot relay preferably is wound to the same resistance.

In connection with the selector I provide resistances 54 and 55 which are of five hundred and one hundred ohms resistance respectively. The entering Morse line 1 is connected to the jacks 16 and 17. This circuit may be traced by following the entrance 20 of the left hand section of the Morse line 1 which is directly connected to the springs 25 and 26.

The springs 25 and 26 are connected by means of a conductor 56 with the left hand 25 terminal of the coil 36 of the relay 35, the right hand terminal of which is connected by means of conductor 57 with the back contact 45. A conductor 58 then connects the coöperating contact spring 44 to the 30 right hand terminal of the coil 37, from which a conductor 59 extends which is connected directly to the back contact 32. A conductor 60 connects the contact spring 28 with the back contact 31 and the coöperating 35 tip spring 27 is then connected to the right hand section of the Morse line 1. The Morse circuit thus extends through the substation B normally with nothing included in its circuit except the coil 36 of the relay 35. Should the plug 18 be inserted in either 40 jack 16 or 17, then the circuit including the relay 35 is broken at either the back contact 31 or back contact 32, but the telegraph instruments associated with the plug 45 are thereupon serially included in the Morse line.

Assume now that the plug 18 is not in either jack and that a code signal is being received over the line 1, this code signal 50 actuates the relay 35 so that its armature 38 moves in unison, thereby transmitting the code to the selector 9 over the circuit which extends from the ground 39, armature 38, front contact 40, conductor 61, coil 10 of the 55 selector 9, resistance 54, conductor 62, conductor 63, battery 48 to ground at 47. The selector 9 is thus actuated in response to the code which is being transmitted over the line circuit 1. If the proper code is received to cause a response on the part of the selector 9, then the contacts 11 and 12 are closed, as is well understood. A closure of 60 these contacts establishes a circuit for the call bell 15. It may also be said that immediately the contacts 11 and 12 are closed the

circuit of the elements 38 and 40 remains closed so long as the operator at station A wishes to continue the operation of the call bell 15. Thus, after the operator at the station A has rung the bell 15 a sufficient length 70 of time, an opening of the circuit of the line 1 will cause a release of the elements 38 and 40, whereupon the selector 9 is restored to normal position. The circuit which is used to operate the call bell when the proper code 75 has been received may be traced from the ground at 47, battery 48, conductor 63, resistance 55, contacts 12 and 11, conductor 64, electromagnet 41, conductor 65, contact 43, armature 42, conductor 66, through the relay 50 to ground at 53. The bell thus operates intermittently by reason of the intermittent character of the contact between the elements 42 and 43. The bell continues operating so long as the circuit between the 85 elements 38 and 40 remains closed. This circuit also causes the locking relay 50 to draw up its armature 51 and thereby establish contact between the elements 51 and 52, whereupon a circuit is established extending 90 from the ground 53, through the coil 50, armature 51, front contact 52, conductor 67, spring 29, back contact 33, conductor 68, lamp 21, conductor 69, back contact 34, spring 30, lamp 22, conductor 70, pilot relay 95 23, battery 48, to ground at 47. This circuit then remains in its locked condition so long as the circuit to either of the back contacts 33 or 34 is not broken by the insertion of the plug 18 into either jack. The insertion of the plug into either jack however restores this circuit and extinguishes lamps 21, 22 and 24. It must be understood that these lamps 21, 22, and 24 continue burning even after the operator at station A has discontinued the operation of the call bell 15 so that a permanent signal is established to call an operator to that particular line as soon as the operator is available.

Now in order to prevent breaking of the 110 circuit between elements 38 and 40 by the opening and closing of the circuit between the elements 42 and 43, I provide the auxiliary winding 37 for the relay 35. This winding 37 is normally short circuited by 115 the establishment of contact between the elements 44 and 45. When the call bell is operating, however, to open the circuit through the coil 36 by reason of the breaking of the contact between elements 44 and 45, then 120 current still passes through the coil 37, which current is enough to maintain the armature 38 attracted although the current would not be enough to attract the armature were it in its unattracted position. The coil 37 is thus merely a holding coil to prevent the release of the armature 38 by reason of the making and breaking of the contacts at the call bell. However, it will be readily 125 apparent that the actuation of the call bell 130

thus serves to change the resistance included in the line 1 at the substation B from one hundred ohms to thirty thousand ohms by reason of the alternate inclusion of the coil 36 and then the coil 37 in the circuit when this call bell is operating. This check in the resistance is sufficient to cause an actuation of the relay 6 at the sending station A to indicate to the operator at that station that 10 the call bell 15 of the substation B is responding to the call.

From what has been thus described it will be readily apparent that the actuating call bell has vibratory means which actually 15 cause a change in the circuit conditions of the line 1 sufficient to operate the relay at the sending station, whereby the sending station receives an answer back signal.

Those skilled in the art will readily understand that my invention may be applied to different systems and under different conditions without departing from its spirit.

Having however thus described one form which my invention may take, what I claim 25 as new and desire to secure by Letters Patent is:

1. A signaling system of the character described comprising a signal sending station and signal receiving station, an electromagnetic signal receiving device at the signal sending station, a line circuit extending between said signal sending and signal receiving stations, a code selector at the signal receiving station, a signal controlled thereby 30 having a vibrating armature and cooperating contact, said code selector having means operable upon the response of said code selector to cause a continuous actuation of said signal during the maintenance of a closed circuit 35 through said code selector, and means including an auxiliary contact under the control of the vibrating armature of said signal to effect changes in the circuit condition of the said line circuit to thereby transmit a 40 signal to operate the signal receiving device 45 at the signal sending station.

2. A signaling system of the character described comprising a signal sending station and signal receiving station, an electromagnetic signal receiving device at the signal sending station, a line circuit extending between said signal sending and signal receiving stations, a code selector at the signal receiving station, a signal controlled thereby 50 having a vibrating armature and cooperating contact, said code selector having means operable upon the response of said code selector to cause a continuous actuation of said signal during the maintenance of a closed circuit 55 through said code selector, and means including an auxiliary contact under the control of the vibrating armature of said signal to effect changes in the circuit condition of the said line circuit to thereby transmit a 60 signal to operate the signal receiving de-

vice at the signal sending station, during maintenance of the closed circuit condition of said code selector.

3. A signaling system of the character described comprising a signal sending station and signal receiving station, an electromagnetic signal receiving device at the signal sending station, a line circuit extending between said signal sending and signal receiving stations, a code selector at the signal receiving station, a signal controlled thereby having a vibrating armature, said code selector having means operable upon the response of said code selector to cause a continuous actuation of said signal during the maintenance of a closed circuit through said code selector, and means under the control of the vibrating armature of said signal to effect changes in the circuit condition of said line circuit to thereby transmit a signal to operate the signal receiving device at the signal sending station, said means including a pair of electromagnets of widely different resistances.

4. A signaling system of the character described comprising a signal sending station and signal receiving station, an electromagnetic signal receiving device at the signal sending station, a line circuit extending between said signal sending and signal receiving stations, a code selector at the signal receiving station, a signal controlled thereby having a vibrating armature, said code selector having means operable upon the response of said code selector to cause a continuous actuation of said signal during the maintenance of a closed circuit through said code selector, and means under the control of the vibrating armature of said signal to effect changes in the circuit condition of said line circuit to thereby transmit a signal to operate the signal receiving device at the signal sending station, during maintenance of the closed circuit condition of said code selector, said means including a pair of electromagnets of widely different resistances.

5. A signaling system of the character described comprising a signal sending station and signal receiving station, an electromagnetic signal receiving device at the signal sending station, a line circuit extending between said signal sending and signal receiving stations, a code selector at the signal receiving station, a signal controlled thereby having a vibrating armature, said code selector having means operable upon the response of said code selector to cause a continuous actuation of said signal during the maintenance of a closed circuit through said code selector, and means under the control of the vibrating armature of said signal to effect changes in the circuit condition of said line circuit to thereby transmit a signal to operate the signal receiving device at the

- signal sending station, said means including a pair of electromagnets of widely different resistances, and an auxiliary vibratory contact making and breaking device operable conformably to the operations of said signal.
6. A signaling system of the character described comprising a signal sending station and signal receiving station, an electromagnetic signal receiving device at the signal sending station, a line circuit extending between said sending and signal receiving stations, a code selector at the signal receiving station, a signal controlled thereby having a vibrating armature, said code selector having means operable upon the response of said code selector to cause a continuous actuation of said signal during the maintenance of a closed circuit through said code selector, and said means under the control of the vibrating armature of said signal to effect changes in the circuit condition of said line circuit to thereby transmit a signal to operate the signal receiving device at the signal sending station.
- 10 15 20 25 30 35 40 45 50 55 60 65 70
7. A signaling system of the character described comprising a signal sending station and signal receiving station, an electromagnetic signal receiving device at the signal sending station, a line circuit extending between said signal sending the signal receiving stations, a code selector at the signal receiving station, a signal controlled thereby having a vibrating armature, said code selector having means operable upon the response of said signal during the maintenance of a closed circuit through said code selector, pilot lamps and a locking relay controlled by said code selector, and means under the control of the vibrating armature of said signal to effect changes in the circuit condition of said line circuit to thereby transmit a signal to operate the signal receiving device at the signal sending station, and maintain the closed circuit condition of said code selector.
8. A signaling system of the character described comprising a signal sending station and signal receiving station, an electromagnetic signal receiving device at the signal sending station, a line circuit extending between said signal sending and signal receiving stations, a code selector at the signal receiving station, a signal controlled

thereby having a vibrating armature, said code selector having means operable upon the response of said code selector to cause a continuous actuation of said signal during the maintenance of a closed circuit through said code selector, pilot lamps and a locking relay controlled by said code selector, and means under the control of the vibrating armature of said signal to effect changes in the circuit condition of said line circuit to thereby transmit a signal to operate the signal receiving device at the signal sending station.

40 45 50 55 60 65 70

8. A signaling system of the character described comprising a signal sending station and signal receiving station, an electromagnetic signal receiving device at the signal sending station, a line circuit extending between said signal sending the signal receiving stations, a code selector at the signal receiving station, a signal controlled thereby having a vibrating armature, said code selector having means operable upon the response of said signal during the maintenance of a closed circuit through said code selector, pilot lamps and a locking relay controlled by said code selector, and means under the control of the vibrating armature of said signal to effect changes in the circuit condition of said line circuit to thereby transmit a signal to operate the signal receiving device at the signal sending station, and maintain the closed circuit condition of said code selector.

In witness whereof I hereunto subscribe my name this 4th day of February, A. D. 1918.
